UNITED STATES PATENT OFFICE.

WILLIAM STARLING BURGESS, OF BROOKLINE, MASSACHUSETTS.

RECOIL-OPERATED GUN.

SPECIFICATION forming part of Letters Patent No. 591,155, dated October 5, 1897.

Application filed November 2, 1896. Serial No. 610,791. (No model.)

To all whom it may concern:

Be it known that I, WILLIAM STARLING BURGESS, of Brookline, county of Norfolk, State of Massachusetts, have invented an Improvement in Rapid-Fire or Machine Guns, of which the following description, in connection with the accompanying drawings, is a specification, like letters and figures on the drawings representing like parts.

This invention has for its object the production of a simple, direct-acting, rapid-fire or machine gun of that class wherein the charges are delivered successively one after another to the loading-chamber from a suitable magazine, the recoil being utilized to automatically reset the parts of and load the gun preparatory to the discharge of the next shot. I have aimed to reduce the number of parts in so far as is compatible with accuracy and rapidity of operation, thus simplifying and reducing the mechanism without decreasing the strength and integrity of the structure. I have shown herein a novel form of magazine as forming part of my invention, but it will be understood that if desired any other suitable form of magazine may be employed.

Various novel features of my invention will be hereinafter fully described in the specification and particularly pointed out in the claims.

Figure 1, in side elevation and partly broken out, represents a gun embodying my invention in loading position with the magazine in place. Fig. 2 is an enlarged longitudinal sectional view through the longitudinal axis of the barrel with the parts in firing position, the magazine being omitted. Fig. 3 is a similar view, the magazine being partially shown and with the parts of the gun in loading position and taken on the line x x , Fig. 7. Fig. 4 is a horizontal sectional view of the main portion of the gun, taken on the longitudinal axis of the barrel, with the parts in the position shown in Fig. 3. Fig. 5 is a transverse sectional view of the barrel and its support, taken on the line x' , Fig. 3, through the breech-chamber. Fig. 6 is a transverse sectional view of the gun on the line x^2 x^2 , Fig. 3, through the trunnions. Fig. 7 is an enlarged top or plan view of a portion of the gun, the front end thereof being broken off

to save space, the magazine being shown in section. Fig. 8 is a transverse sectional view of the rear end of the gun, through the back piece, on the line x^3 x^3 , Fig. 3. Fig. 9 is an enlarged perspective detail of the breech-block. Fig. 10 is an enlarged horizontal sectional view of the shell carrier or transerrer. Fig. 11 is a transverse section thereof on the line x^4 x^4 , Fig. 10. Fig. 12 is a detail, partly in section, of the magazine-actuating pawl; and Fig. 13 is a perspective view, broken out between its ends, of the gun-frame detached, the sheet-metal casing being omitted at the rear end of the frame. Fig. 14 is a perspective detail view of the breech-block guide and barrel-jacket, the latter being broken off at its front end. Fig. 15 is a longitudinal sectional view of the breech-block and parts carried thereby, the breech-block and said parts being shown in the same position as in Fig. 3; and Fig. 16 is a like view showing the breech-block in locked position and with the firing-pin ready to be released to fire the gun.

I have herein shown the gun-frame as comprising four rigid metal bars a , extended in parallelism with the longitudinal axis of the gun and preferably square in cross-section, rigidly secured at their ends to forgings a' and a^2 in suitable manner, as by bolts or rivets 1 and 2, respectively, and also to an intermediate trunnion-band a^3 , herein shown as by rivets 3, the said band having suitable trunnions a^4 , by which the gun may be supported on the head of a tripod T, Fig. 1, or other desired form of mount.

As shown in Figs. 5, 6, and 8, the bars a of the frame are arranged in the form of a rectangular figure, giving great strength with lightness and providing ample space and support for the operative parts of the gun.

The forging a^2 , which may be termed the "back piece," is shown in Figs. 8 and 13 as enlarged at its upper end and recessed to receive the side bars a , between the pairs of which at each side the breech-block and breech-block support or guide C^x , to be described, are movable, the back piece being cut out at a^4 to receive the breech-block guide, the said guide being rigidly attached to the gun-barrel, while the depending portion a^6 of said back piece provides a support for some of the controlling devices. A sheet-metal

casing a^{10} preferably surrounds the side bars a at top and sides, passing through the open trunnion-band a^3 , (see Figs. 6 and 13, wherein said casing is shown in elevation to avoid confusion,) the band being concaved at its sides at a^3 to receive longitudinal convex portions a^{12} on the casing sides, which latter inclose spiral retracting or recoil springs S of suitable strength, adjustably attached at their outer ends to the front plate a' of the frame and at their inner ends to the barrel extension or breech-block guide C^x by laterally-extended lugs c^x thereon, the said lugs sliding between and being guided by the two side bars a at each side of the frame.

The barrel B , having a suitable bore b and breech-chamber b' of suitable shape to receive the cartridge, is rigidly secured by shrinking or other suitable means to a jacket C , surrounding the barrel for a portion of its length, and, as shown in Figs. 5 and 6, is square in cross-section to enter the space between the side bars a of the frame.

The jacket is provided at each side with laterally-extended lugs C' , which enter between and are guided by the two bars a at each side of the frame, the lugs being extended adjacent the jacket at a to bear against the vertical inner faces of the side bars.

At the rear or inner end of the barrel the jacket is bifurcated and extended rearwardly through the back piece a^2 , the two sides of such extension C^x forming a support or guide for the breech-block, as will be described, the inner faces of the extensions being recessed at c and provided near their lower ends with shoulders c' to receive and support and guide the breech-block D . (Shown separately in Fig. 9.)

The breech-block is shown as comprising a slide-bar d , which enters the recess c of its support, said slide-bar at its rear end having separated downturned extensions d' , which rest and slide upon the longitudinal shoulders c' on the breech-block guide C^x , and the breech-block is cut out or recessed to form a longitudinal opening d^2 , enlarged between its ends at d^3 , the inner faces of the extensions d' being recessed at d^4 , Figs. 2, 3, and 8, forming curved shoulders d^5 , the recesses forming a chamber to receive a locking-block e , pivoted at e' in the breech-block and adapted to enter when in locking position a notch c^2 in the connecting portion C^2 of the extensions C^x , said cross-piece or connecting portion being recessed at the rear of the notch to leave a vertical shoulder c^3 , with which co-operates a dog e^2 , forming a part of the locking-block e , when the latter is rocked, as will be described, by the recoil of the gun. At the instant of discharge the shoulders d^5 transmit the recoil shock from the breech-block through the lock e to the breech-block guide C^x , thereby causing the barrel and attached breech-block guide to recoil.

A lever f is pivotally connected at its lower end by a short link f' to the extension a^6 of

the back piece, as clearly shown in Fig. 1, the upper end of the lever being extended between the sides of the breech-block guide C^x 70 and having pivoted thereto at f^2 an arm f^3 , through an opening f^4 of which is extended an upturned finger e^3 , forming a rigid part of the locking-block e , the under side of the arm f^3 being notched at f^5 to be engaged by a detent f^6 , pivoted at f^7 in a slot at the rear end of the breech-block and controlled by a spring s .

The detent is provided with a laterally-offset toe f^8 in the path of and to be engaged by 80 a shoulder c^4 on one of the extension-pieces or sides C^x , as clearly shown in Fig. 8.

The cross connection C^2 of the breech-block guide C^x is reduced in width and downturned to form a foot C^3 , through which is extended 85 a slide-rod f^9 , pivoted at f^{10} on the lever f , the lever-arm between f^{10} and f^2 being substantially twice as great as the length of the lever-arm from f^{10} to the link f' , so that the speed of movement of the upper extremity of 90 the lever will be substantially three times that of the slide-rod f^9 , for a purpose to be described, said slide-rod having an annular enlargement or flange f^{12} thereon at the rear of the foot C^3 , a spiral spring s' surrounding 95 the rod between the front of the foot and an adjustable collar f^{13} , held on the threaded front end of the slide-rod.

The flattened portion d of the breech-block has upon its under side a longitudinally-extended rounded tubular portion d^6 to inclose the firing-pin g , (see Figs. 2, 3, and 11,) the forward end of the part d being transversely recessed at its under side at d^7 , while the tubular enlargement is carried beyond the 105 breech-block, as at d^8 , Fig. 9, and cylindrical in form to enter and close the breech-chamber when the cartridge is in place.

Cartridge-gripping jaws j are pivoted at j' to the breech-block in the recess d^7 , one at 110 each side of the tubular extension d^8 , said jaws at their forward ends being slightly concaved longitudinally at j^x , Fig. 10, to embrace the sides of the cartridge-case. The jaws are normally separated by suitable leaf-springs 115 s^2 , interposed between them and the projecting part d^8 , as clearly shown in Fig. 10, the jaws and enlargement being preferably recessed to hold the springs in place. The jaws are extended rearwardly beyond their 120 pivots and inturned at j^2 to enter small holes d^9 in the tubular enlargement d^6 of the breech-block, the said ends j^2 of the jaws co-operating with and being controlled by the firing-pin, which is reduced in diameter at g' and 125 enlarged to elliptical form in cross-section at g^2 at its front end.

By referring to Fig. 10 it will be obvious that when the firing-pin is drawn back, or to 130 the left viewing said figure, the gradual enlargement thereof will act upon the inturned ends j^2 of the gripping-jaws to separate them and thereby close the outer or gripping faces of the jaws upon a cartridge H , the shoul-

ders j^3 , formed at the inner ends of the gripping-faces, closing over the usual base-ring or enlargement of the cartridge-case to extract the latter after firing.

- 5 The firing-pin is extended through the breech-block into the recess d^2 therein and has secured thereto a block g^3 , acted upon by a suitable firing-spring s^3 , rigidly secured at one end to a pin 9 in the breech-block.
- 10 The block g^3 has extended rearwardly therefrom a latch g^4 , to be engaged when the firing-pin is withdrawn by a suitable notched sear g^5 , pivoted at g^6 to the breech-block and normally held by a spring s^4 against a stop-pin 15 or projection 12 , the sear being released or tripped by a suitable wiper t' , fast on a rock-shaft t , supported in suitable bearings t^x on the gun-frame and actuated by a trigger T of suitable construction, movement of the trigger causing the wiper t' to wipe over and depress the tail g^7 of the sear when the latter is 20 in the position shown in Figs. 2 and 16, to thereby trip the sear, releasing the latch g^4 and permitting the firing-spring s^3 to throw 25 the firing-pin and fire the cartridge.

By referring to Figs. 3 and 15, wherein the parts of the gun are shown in extended position ready to load, it will be seen that the firing-pin is, relatively to the breech-block, 30 in firing position, and it will be obvious that said firing-pin must be withdrawn in the breech-block into the retracted position shown in Figs. 2 and 16 in engagement with the sear before the cartridge is inserted in 35 the barrel.

Referring now to Fig. 2, let it be supposed that the gun is fired. Then the firing-pin, having been thrown forward by its actuating-spring s^3 until it strikes the cartridge, assumes a position relative to the breech-block substantially as shown in Fig. 3. At the instant of discharge, however, the recoil of the gun acts, through the breech-block and lock e , upon the foot C^3 , forming a part of the 40 breech-block guide C^x , to throw the lever f from the position shown in Fig. 2 in the direction of the arrow 25. The upper end of the lever moving more rapidly acts, through its arm f^3 , to turn the locking-block e on its 45 fulcrum e' , the dog e^2 acting upon the vertical shoulder c^3 as soon as the block leaves its holding-recess c^2 to slowly move the breech-block relatively to its guide to thereby start the cartridge from the breech-block chamber, 50 such retarded movement of the breech-block continuing until the shoulders f^x on the arm f^3 engage the lowermost shoulders 20 of the enlarged part d^3 of the recess in the breech-block. Thereafter as the upper end of the 55 lever f continues to move in the direction of the arrow 25, Fig. 2, the breech-block must move in unison therewith, and such movement of the breech-block continues until the gradually-decreasing force of the recoil is 60 equalized by the tension of the retracting-springs S , the parts in such position being 65 slightly farther to the left than as shown in

Fig. 3. Just after the initial movement of the breech-block described the notch f^5 of the arm f^3 moves past the detent f^6 , and when 70 the outward movement of the breech-block ceases and its inward movement begins, due to the tension of the retracting-springs S , the detent enters the notch, as shown in Fig. 3, so that the locking-block e will be held in the 75 position shown in Fig. 3 until positively released, and the breech-block must travel in unison with the upper end of the lever f .

The breech-block and firing-pin will start in unison in the direction of the arrow 30, 80 Fig. 3, and the firing-pin is not retracted relatively to the breech-block until a spring-controlled locking-pawl g^{10} on the block g^3 engages the shoulder c^4 on the breech-block guide C^x , thereby retarding or holding the 85 firing-pin until the sear g^5 , carried by the breech-block, advances far enough to engage the latch g^4 , and the beveled end of the locking-pawl g^{10} is then engaged and tripped by a pin 18 on the breech-block, the tripped 90 pawl being shown clearly in Fig. 2 with the sear in engagement with the firing-pin latch g^4 . After the trip of the pawl g^{10} the firing-pin and breech-block continue their movement together until the toe f^8 of the detent 95 f^6 in turn is engaged by the shoulder c^4 , withdrawing the detent from engagement with the arm f^3 and disconnecting the lever f and breech-block, the latter then closing the breech, and the continued movement of the 100 lever f then acts to turn the locking-block e from its fulcrum into engagement with the locking-notch c^2 .

The spring s' will act as a buffer or cushion for the barrel to prevent shock as the 105 breech of the barrel is closed by the breech-block, it being remembered that the lower end of the lever f has its fulcrum fixed or stationary. The spring s' is of such strength that during almost the entire inward movement of the breech-block and guide the flange f^{12} will be held against the foot C^3 , and when the breech-block is fully entered into the breech the upper end of the lever cannot move farther relatively to the breech-block 115 guide C^x , and should the barrel and the attached breech-block guide tend to move still farther forward, due to its inertia, then the spring s' would be compressed by the foot C^3 moving with the barrel, and said spring would 120 then act as a buffer or cushion.

The breech-block guide C^x is provided with a cartridge-support c^{10} to receive a fresh cartridge from the magazine, to be described, the support being so located that the plate 125 portion d of the breech-block slides back and forth over said support in the movement of the block.

When the gun is in firing position, Fig. 2, the breech-block is shown as extended over 130 the cartridge-support, and when the breech-block moves forward from the position shown in Fig. 3 the jaws j thereof will engage and grip the cartridge then on the support, the

closing of the jaws being effected by retraction of the firing-pin g , as has been described.

After the cartridge is gripped forward movement of the breech-block will transfer the cartridge from the support c^{10} across the open space c^{15} between it and the breech of the barrel, and the cartridge will finally be inserted in the breech-chamber b' . The support c^{10} is below a horizontal line passing through the bore 10 of the barrel, in order that the forwardly-extended portion d of the breech-block can slide over said support in its return movement, and the nose of the projectile will lift slightly on entering the breech-chamber to properly 15 position the projectile.

Referring to Figs. 4 and 5, it will be seen that the breech-chamber is laterally recessed at b^2 to receive the forward ends of the jaws as they are closed upon the cartridge, while 20 the tubular portion d^3 of the breech-block enters and completely closes the rear end of the chamber.

When the gun is discharged, the firing-pin g is thrown forward by its spring s^3 , so that 25 the enlarged portion g^2 thereof is moved toward the outer ends of the jaws and bringing the reduced portion g' opposite the inturned ends j^2 of said jaws, so that when the breech-block is retracted, as has been described, the 30 jaw-springs s^2 will open them as soon as they pass beyond the retaining-walls 35 (see Fig. 4) of the breech-block guide immediately at the rear of the breech of the barrel, so that the empty cartridge-case will not be released by 35 the grippers until it is sufficiently withdrawn from the breech-chamber to insure its discharge therefrom through the opening c^{15} described.

The casing α^{10} is cut away above the cartridge-support c^{10} to form a guide-chute a^{15} , through which the cartridges are delivered or pass one by one from the magazine, now to be described.

The magazine consists, essentially, of a cylinder M , closed at its lower end, except for the elongated radially-disposed opening m , and provided with a foot M' , shown in Fig. 3 as extended into a suitable recess in the trunnion-ring α^3 , the cylinder at its opposite 45 side having an exterior lug to form a slightly-concaved seat m' for the eccentrically-mounted locking-stud m^3 on a yoke m^3 , pivoted at m^4 on the gun-frame, the eccentric locking-stud m^2 having a suitable handle m^5 . If the 50 handle is turned down to the left, Fig. 3, the stud will be rocked to lift it from its seat m' and the yoke m^3 can be turned upon its pivot to withdraw the locking-stud, so that the magazine may be removed, when desired, for 55 recharging or refilling.

The bottom of the cylinder M has an upturned central boss m^6 to support a grid m^7 , mounted to rotate on a vertical pin or stud m^8 , the said grid, as best shown in Fig. 7, 65 having a series of radial openings or pockets m^9 therein of such shape and size as to permit the passage therethrough of a single car-

tridge at a time, the depth of the grid being about equal to the diameter of the cartridge.

Upon the interior of the cylinder M are secured in suitable manner a series of stalls N , each stall being preferably composed of sheet metal or suitable light material and in cross-section, as shown in Fig. 7, having a shape approximating that of a cartridge. These stalls 70 extend from just above the grid m^7 to substantially the upper end of the cylinder M , and when the magazine is charged each stall is filled with a series of cartridges, resting 75 one upon another, the lowermost cartridge of the series, however, entering the pocket m^9 of the grid which is beneath the stall, and thus supporting the superimposed cartridges 80 in that particular stall.

It will be obvious from the foregoing description that if the grid is rotated intermittently to bring one pocket after another over the discharge-chute a^{15} the pockets will each discharge a cartridge therefrom into the chute.

There is no stall in the magazine immediately above the discharge-chute a^{15} , and when a cartridge is discharged from the grid, which is practically a carrier or transerrer, the empty pocket at the next movement of the transerrer will be moved beneath the stall 95 next beyond to receive therefrom the lowermost cartridge of its series, and that cartridge would make one nearly complete revolution with the transerrer before being brought into position above the chute a^{15} . It will be seen, 100 therefore, that the first stall beyond the discharge-opening m of the magazine will be the first stall emptied, and then the second stall will be emptied, then the third, and so on until the cartridges have been transferred 105 from all of the stalls in the magazine to the cartridge-support c^{10} .

The cylinder M has mounted therein a shaft n , transverse to the length of the gun and provided inside the cylinder with a cam n' in engagement with an arm n^2 , pivoted at one end at n^3 on the cylinder-wall and slotted or forked at n^4 at its other end to receive a slide-rod n^5 , vertically movable in the bearing m^{10} on the cylinder and normally depressed by a spring 110 s^6 , the upper end of which may be held against the top or cap of the cylinder.

The slide-rod n^5 is located in the vertical plane of the discharge-opening m of the magazine and is headed at its lower end at n^6 to 115 yieldingly bear upon a cartridge on its support c^{10} and retain it in place until firmly gripped by the jaws carried by the breech-block.

The rock-shaft n is extended through the wall of the magazine-cylinder M and has fast 120 thereon a rocker-arm n^7 , the lower end of which is engaged by a suitable yoke n^8 , suitably bolted to the breech-block guide to move therewith and from which it may be readily detached when it is desired to remove the 125 breech from the frame.

When the barrel and breech-block guide move forward, the rock-shaft n will be partially rotated to lift the cam n' and thereby

the arm n^2 , the latter raising the headed slide-rod n^5 from engagement with the cartridge, as the latter is then firmly held by the gripping-jaws, and the slide-rod continues to rise 5 until its head assumes about the dotted-line position n^6 , Fig. 3.

The transferrer or grid m^7 is provided with a series of peripheral pins or projections m^{18} , which are exposed through a horizontal slot 10 in the wall of the cylinder M to the action of a spring-pawl m^{14} , mounted in ears n^{20} on the rocker-arm n^7 and controlled by a suitable spring s^{10} .

Just as the head n^6 of the slide-rod clears 15 the top of the grid or transferrer the pawl m^{14} will engage one of the projections m^{18} of the transferrer, and as the rocker-arm n^7 completes its movement, due to the movement of the breech-block guide, the transferrer will 20 be rotated one step, or sufficiently to bring a new pocket over the discharge-opening m . A suitable detent-pawl m^{15} prevents retrograde motion of the transferrer as the arm n^7 is swung back by the recoil into the position 25 shown in Fig. 1 and the pawl m^{14} clicks back ready to engage the next succeeding projection on the following forward stroke of the rocker-arm. When the rocker-arm swings rearwardly, the cam n' is depressed, permitting 30 the spring s^6 to act upon the slide-rod n^5 and follow the transferred cartridge down through the chute a^{15} onto the support c^{10} as soon as the portion b of the breech-block slides back from off the support.

35 Referring to Figs. 2, 3, 15, and 16, I have shown a cover-plate D^{10} , secured to the rear end of the breech-block and covering or protecting the mechanism carried by said block between the depending portions d' thereof, 40 the cover-plate being cut away at 80 to permit the passage therethrough of the upturned end of the sear g^5 to allow the wiper t' to co-operate therewith, said cover-plate also having a suitable opening to accommodate the upturned portion e^8 of the locking-block.

A suitable shoulder-rest R (shown only in Fig. 1) is secured to the gun-frame and is adapted to be held against the shoulder of the operator when the gun is in use in order to 50 train or direct the gun, as may be desired. Suitable sights will be provided in usual manner, and to prevent accidental movement of the trigger the same is protected by a guard T^X , partly broken out in Fig. 7 and only indicated by dotted lines in Fig. 3.

55 The trigger is provided with a trigger-spring S^{10} , (see dotted lines, Fig. 3, and full lines, Fig. 7,) tending to normally retain the trigger and wiper t in the position shown in Fig. 2. 60 If the dotted-line position of the wiper in Fig. 2 is referred to, it will be seen that by holding the trigger retracted the gun will operate automatically, for the portion g^7 of the sear will be engaged by the wiper at every 65 forward or firing movement of the breech-

block to thereby release the firing-pin and discharge the gun.

Inasmuch as the operation of the gun mechanism is due to the recoil it is necessary before firing the first shot to draw back the breech-block and breech-block guide into the position shown in Fig. 1 by hand, and for this purpose I have secured a suitable handhold or grip G to one side of the breech-block guide C^X . In order, therefore, to begin firing, the operator will first grasp the handhold G and draw the breech-block guide rearwardly until a cartridge has been transferred from the magazine to the cartridge-support c^{10} , whereupon the handhold is released and the gun 80 loaded by virtue of the recoil-springs S . Thereafter the gun will automatically load after each shot fired, as has been hereinbefore described.

My invention is not restricted to the precise 85 construction and arrangement herein shown, as the same may be modified without departing from the spirit and scope of my invention.

If desired or found necessary, the barrel may be provided with a water-jacket of any 90 usual or suitable construction.

Having fully described my invention, what I claim, and desire to secure by Letters Patent, is—

1. In a machine-gun, a supporting-frame, 95 the barrel longitudinally movable therein, a barrel-retracting spring, means to at times lock the barrel and breech-block from relative movement, a spring-controlled firing-pin carried by the breech-block, outwardly movable therewith, cocking mechanism for the pin, automatically operated upon return of the breech-block, a manually-controlled releasing device for said mechanism, actuating mechanism for the breech-block governed by 100 the recoil, and connections between said mechanism and the locking means, to control the latter, substantially as described.

2. In a machine-gun, a breech-block reciprocable in the direction of the length of the barrel, and moved in one direction by the recoil, means to positively move it in the opposite direction, a spring-controlled firing-pin longitudinally movable in said block, mechanism to retain the firing-pin stationary during a portion of such latter movement of the breech-block, a releasing device for the pin, operative when the breech-block is locked, and a locking device for said breech-block to retain it in firing position, substantially as 115 described.

3. In a machine-gun, a longitudinally-movable breech-block guide, a breech-block reciprocable thereon, means, actuated by the recoil, and including an accelerating-lever to 125 move the breech-block and its guide outwardly at different speeds, and a locking device for the breech-block, governed by said means, combined with means carried by the breech-block to positively retain the locking 130

device inoperative during the return movement of the breech-block, and a trip to release the locking device when the breech-block reaches the end of such movement, substantially as described.

4. In a machine-gun, a longitudinally-movable breech-block guide, a breech-block reciprocable thereon, means, actuated by the recoil, to move the breech-block and guide outwardly at different speeds, a detent for the breech-block, operative during a portion of its inward movement, a locking device for the breech-block, governed by said actuating means, and a trip for the detent, substantially as described.

5. In a machine-gun, a longitudinally-movable breech-block guide, a breech-block reciprocable thereon, a spring-controlled firing-pin longitudinally movable in said breech-block, the barrel rigidly attached to the said guide, a supporting-frame in which the barrel and guide are movable, mechanism to cock or set the firing-pin on the inward movement of the breech-block, means, actuated by the recoil, to move the breech-block outwardly and relatively to its guide, a retracting-spring to effect the return of the barrel and guide to normal position, to thereby move the breech-block inward, and a releasing device for the firing-pin, substantially as described.

6. In a machine-gun, a breech-block reciprocable in the direction of the length of the barrel, means controlled by the recoil to actuate the breech-block, a firing-pin longitudinally movable in said breech-block, its actuating-spring, a sear mounted on the block, a coöperating latch on the firing-pin, and means to hold the firing-pin stationary relatively to the breech-block on the inward movement of the latter, substantially as described.

7. In a machine-gun, a breech-block reciprocable in the direction of the length of the barrel, means controlled by the recoil to actuate the breech-block, a spring-controlled firing-pin longitudinally movable in said breech-block, means to set or cock the pin on the inward movement of the breech-block, and a sear and coöperating latch, to retain the firing-pin cocked, substantially as described.

8. In a machine-gun, a breech-block reciprocable in the direction of the length of the barrel, means controlled by the recoil to actuate the breech-block, a spring-controlled firing-pin longitudinally movable in said breech-block, means to set or cock the pin on the inward movement of the breech-block, and a trip for said means, a sear and coöperating latch, to retain the pin cocked, and means controlled by a trigger to disengage the sear and latch, substantially as described.

9. In a machine-gun, a breech-block guide, a breech-block reciprocable thereon, a spring-controlled firing-pin longitudinally movable in said breech-block, means to automatically set it on the inward movement of the breech-block, means actuated by the recoil to oper-

ate the breech-block, cartridge-gripping devices mounted on the latter, to grip a cartridge, insert it in the barrel, and eject the empty shell, and means, controlled jointly by movement of the breech-block and firing-pin to operate said gripping devices, substantially as described.

10. In a machine-gun, the barrel and attached breech-block guide, a breech-block reciprocable in the latter, a supporting-frame on which the barrel and guide are longitudinally movable, retractile springs for the barrel, means, actuated by the recoil, to move the breech-block outwardly, and a buffer forming a part of said means to cushion the return of the barrel to firing position, substantially as described.

11. In a machine-gun, the barrel and attached bifurcated breech-block guide provided with a shoulder, a breech-block reciprocable in and between the sides of the latter, a supporting-frame on which the barrel and guide are longitudinally movable, retractile springs for the barrel, means, actuated by the recoil, to move the breech-block outwardly, a locking device pivotally mounted on the block to at times lock the breech-block to its guide, a dog, forming a part of said locking device and means to rock said device to bring the dog into engagement with the shoulder and thereby effect a slow initial movement to the breech-block and guide in unison and to thereafter fully release the locking device, substantially as described.

12. In a machine-gun, an open supporting-frame, comprising upper and lower side bars in parallelism, end pieces and a trunnion-ring rigidly secured thereto, a barrel, and a breech-block guide rigidly attached thereto, both longitudinally movable on said frame and within the side bars thereof, a breech-block reciprocable on its guide, a retractile spring, and a buffer for the barrel upon its return to normal position, substantially as described.

13. In a machine-gun, a longitudinally-movable bifurcated breech-block guide, a breech-block reciprocable within the side walls thereof, means actuated by the recoil, to move said guide and block outward, said means including an accelerating-lever yieldingly connected between its ends to the guide, and connections between the free end of the lever and breech-block, to start the latter slowly, and thereafter to increase the speed of the breech-block relatively to the guide, and a retractile spring to return the said guide to normal position, substantially as described.

14. In a machine-gun, a breech-block, means actuated by the recoil, to cause it to reciprocate in the direction of the length of the barrel, a firing-pin, a device fixed relatively to the breech-block to move the firing-pin into cocking position at or near the beginning of the return movement of the breech-block, means carried by the breech-block to thereafter move forward, engage and retain the

firing-pin cocked, means to release the pin from control of the relatively fixed device, and a manually-operated releasing device for said retaining means, whereby the gun may 5 be discharged automatically or at will, substantially as described.

15. In a machine-gun, the barrel, a breech-block guide movable therewith, and having a locking-notch, a reciprocating recessed 10 breech-block, having curved shoulders, a locking-block pivoted in the recess to rest against the curved shoulders and enter the notch, to thereby lock the breech-block to the guide, accelerating mechanism to reciprocate 15 the breech-block relatively to the guide, connections between said mechanism and the locking-block to rock the latter, and unlock 20 said guide and breech-block, the shoulders transmitting the recoil shock through the locking-block to the guide, and retractile springs to control the recoil of the barrel, substantially as described.

16. A magazine for machine-guns, comprising a fixed cylindrical case having a discharge-opening in its lower end, an intermittently-movable transferer movable over said lower end and having open, cartridge-receiving pockets, means to support a series of superposed cartridges in the case above the transferer to deliver the cartridges one by one to the latter, a follower reciprocable in line with the discharge-opening of the case, to follow a discharged cartridge through said opening, and means to reciprocate the follower, substantially as described.

17. In a machine-gun, a breech-block reciprocable in alinement with the barrel, devices carried by said breech-block to grip a cartridge and insert it in the breech-chamber, a cartridge-magazine having a discharge-opening, a support located below the opening to receive a cartridge from the magazine and support it until engaged by the gripping devices, a transferer to deliver cartridges one 45 by one to the discharge-opening of the maga-

zine, and means to actuate the transferer intermittently, substantially as described.

18. In a machine-gun, a stationary magazine having a discharge-opening in its lower end, a transferer to deliver cartridges singly 50 to said opening, a support below the opening, to receive and sustain a cartridge discharged from the magazine, means operative by the recoil, to actuate the transferer, and a carrier to engage a supported cartridge, and convey it to the breech-chamber, substantially as described.

19. In a machine-gun, a stationary magazine having a discharge-opening in its lower end, a transferer to deliver cartridges singly 60 to said opening, a support below the opening, to receive and sustain a cartridge discharged from the magazine, a follower to yieldingly retain a cartridge on its support, means operative by the recoil, to operate the transferer and follower intermittently, and a carrier to positively engage a supported cartridge and convey it to the breech-chamber, substantially as described.

20. In a machine-gun, the barrel having a 70 breech-chamber provided with lateral recesses, a cartridge-support, a cartridge-carrier having jaws to grip and hold a supported cartridge and convey it to the breech-chamber, means to retain the jaws closed until the 75 empty shell has been withdrawn from the breech-chamber, and mechanism controlled by the recoil, to reciprocate the carrier and operate the jaws, the latter entering the lateral recesses of the breech-chamber when 80 the cartridge is therein, substantially as described.

In testimony whereof I have signed my name to this specification in the presence of two subscribing witnesses.

WILLIAM STARLING BURGESS.
